AUTOMATIC TELEPHONE TRUNKING
SYSTEM

Rodney G. Richardson, Chicago, Ill., assignor, by
mesne assignments, to Associated Electric
Laboratories, Inc., Chicago, Ill., a corporation
of Delaware

Application October 12, 1931. Serial No. 568,349

15 Claims. (Cl. 179—16)

This invention relates to automatic telephone trunking systems, and the object of the invention is to provide new and improved trunking arrangements tending to greater efficiency and 5 economy of apparatus than is found in systems heretofore available.

The invention contemplates the use of so-called "drop-back" or digit-absorbing selectors, such as are shown in the patent to Martin, No. 1,640,551, the patent to Bellamy No. 1,694,615, and the patent to Suekoff, No. 1,581,244. Trunking systems using such drop-back selectors are shown in the patents mentioned. The patent to Lomax, No. 1,747,478, also shows a trunking system 10 using drop-back selectors. These known trunking systems, however, are applicable only to certain particular situations and they afford no solution to problems arising in many other situations. According to the present invention, the use of 20 drop-back selectors is greatly extended. These comparatively inexpensive switches are used in new and unexpected ways to introduce plant economies and to solve trunking problems which heretofore could not be taken care of without the 25 use of much more expensive equipment.

The invention is illustrated in the accompanying drawings in which Fig. 1 is a schematic diagram showing the trunk lines interconnecting the offices or exchanges in a multi-office automatic 30 telephone system; Fig. 2 is a more detailed trunking diagram which shows the trunking in the office A and in the tandem office E of Fig. 1; while Fig. 3 is a detailed trunking diagram which shows a modified form of the invention applied to the 35 individual offices of a two-office system.

Referring to Fig. 1, the system therein depicted comprises a tandem office E and a number of out-lying offices A, B, C, D, and F. It may be assumed that these offices are all standard 10,000-line 40 offices, at least the full quota of 10,000 subscribers' numbers is allotted to each office. A uniform six-digit numbering system is used, that is, each subscriber's number comprises six digits. The first two digits in each number relate to the interoffice trunking, while the last four digits are 45 the so-called local or numerical digits which relate to the local trunking. If desired, of course, the first two digits in the numbers may be replaced by letters.

50 The local trunking in the various offices follows well-known Strowger practice. Connections are completed by means of the usual thousands selectors, hundreds selectors, and connectors, which operate in accordance with the four local 55 digits in subscribers' telephone numbers.

The interoffice trunking features the use of drop-back selectors, according to a systematic plan which has been worked out, providing for tandem trunking while preserving the uniform numbering system. As shown in Fig. 1, the tandem office E is connected with each of the other offices by direct trunk lines. As illustrated, it is assumed that these are one-way trunk lines, although, of course, two-way trunks could be used. There are, therefore, two groups of trunk lines extending between the tandem office E and each of the other offices. One group is for handling traffic from the tandem office to the particular office in question, while the other group handles traffic from such office to the tandem office. There are also groups of direct trunks connecting certain of the outlying offices, as for instance offices A and B, offices B and C, etc. Not all of the outlying offices are thus connected, however. Calls from office A to office F, for instance, are routed via the tandem office E.

50 All this is clearly shown in Fig. 1, in which each group of trunk lines is indicated by a single line drawn between the circles representing offices. Fig. 1 also shows the office digits assigned to each office, and, in connection with the groups of trunk lines, it shows the digits which are dialled to give access to each group. The office designation assigned to office A, for instance, is 23, while the office designation assigned to the tandem office E is 65. The group of trunk lines extending from office E to office A bears the number 23, which indicates that the digits 2 and 3 must be dialled to reach a trunk in this group. The group of trunk lines extending from office A to office E bears the designation 6—5—4—7, which indicates that a trunk in this group may be reached by dialling the digit 6, the digit 5, the digit 4, or the digit 7. The point here is that this group of trunk lines is used for handling traffic from office A to offices E, C, D, and F, and is reached by dialling the first digit of the office designation of any of these latter offices. The numbering of the other groups of trunk lines can readily be understood from the foregoing.

55 Reference may now be had also to Fig. 2 for a more detailed explanation. That portion of Fig. 2 to the left of the dotted line indicates equipment in office A, while the portion to the right indicates equipment in the tandem office E.

At the upper left-hand corner of Fig. 2 a subscriber's station is indicated, the telephone number of which is 23XXXX. The last four digits, being immaterial, are each represented by X. This line has access by way of any well-known 110

switching device, such as the rotary lineswitch RS', to a group of first selectors, one of which is FS'.

On the second level of its bank the first selector FS', in common with other similar selectors, has access to trunk lines extending to local thousands selectors such as MS'. The selectors such as MS' are of the drop-back type, similar to the selectors shown in the Bellamy patent or the Suekoff patent, and they always cancel the first digit received after being seized. The letters (DB) inserted in the rectangle which represents the selector MS' in the drawings indicate that the selector is of the drop-back type and similar labels serve to identify the other selectors of this type.

On the third level of their banks the first selectors such as FS' have access to a group of trunk lines 3, Fig. 1 and Fig. 2, which extend to office B, where they terminate in thousands selectors similar to the thousands selectors MS' or MS2. The latter selectors terminate in trunk lines incoming to office A from office B, and the arrangement in office B is the same as regards the trunk lines incoming from office A.

The fourth, fifth, sixth, and seventh levels of the selectors such as FS' are multiplied together and give access to a group of trunk lines 6-5-4-7, extending to the tandem office E, where they terminate in office selectors such as OS'. These office selectors are standard Strowger switches and do not cancel any digits.

Referring now to office E, there is shown a subscriber's station having the telephone number 65XXXX. This line has access through a rotary lineswitch RS2 to a group of first selectors such as FS2. These first selectors are of the drop-back variety previously mentioned and always cancel the first digit. The banks of the first selectors FS2 are connected in multiple with the banks of the office selectors.

The office selectors comprise, in addition to the office selectors OS' previously mentioned, a group including OS2, a group including OS3, a group including OS4, and a group including OS5. These groups of office selectors terminate groups of trunk lines incoming from offices B, C, D, and F, respectively. The banks of all the office selectors are multiplied together, and with the banks of the first selectors FS2, as previously stated.

On the third level of their banks the office selectors OS' and the first selectors FS2 have access to a group of trunk lines 23 extending to office A, where they terminate in a group of thousands selectors MS3. On the second, fourth, sixth, and eighth levels these office selectors have access to groups of trunk lines extending to offices C, B, F, and D, respectively. These latter groups of trunk lines terminate in groups of thousands selectors similar to MS3.

On the fifth level the office selectors and the first selectors in office E have access to a group of trunk lines extending to the local thousands selector such as MS4. These selectors are standard selectors and do not cancel any digits.

The trunking beyond the thousands selectors is not shown as it is well known. It may be stated, however, that the thousands selectors MS4 in office E have access on the various levels of their banks to groups of hundreds selectors, and these latter in turn to groups of connectors, which have access to the subscribers' lines.

In office A also the thousands selectors, such as MS', MS2, and MS3, have their banks multiplied together and give access to trunk lines ex-

tending to groups of hundreds selectors, which have access to groups of connectors. The same is true of the other offices.

Although statements are made herein without qualification to the effect that banks are multiplied, this may be only partially true in certain cases where large trunk groups are required. It will be understood that the multiple may be sectionalized as desired according to well known principles of grading, or the different groups of switches whose banks are stated to be multiplied may have access on certain levels to separate groups of trunk lines leading to secondary line-switches. These facts do not alter the principles involved, and for simplicity, therefore, the banks of switches of the same order are shown as being directly multiplied together.

It will be convenient now to explain the establishment of a few typical connections. It will be assumed first that the subscriber at station 23XXXX desires to obtain connection with another subscriber in the same office whose telephone number also is 23XXXX differing, of course, in one or more of the last four digits. On removing the receiver, the lineswitch RS' operates to select an idle first selector such as FS'. The first digit 2 of the office designation is then dialled, operating the selector FS' to the second level, whereupon it rotates in and selects an idle thousands selector such as MS'. The second office digit 3 is then dialled and is cancelled by the selector MS', the circuits of the selector being automatically altered at the same time so that the next digit will not be cancelled. The four local digits are dialled next, the first digit operating the selector MS' to select an idle hundreds selector in the desired thousand, the second operating the selected hundreds selector to select a connector in the desired hundred, and the third and fourth local digits operating the selected connector to select and connect with the desired subscriber's line. The switches are released in the usual manner when the calling subscriber hangs up the receiver.

It will be assumed now that the subscriber at station 23XXXX desires to extend a call to the subscriber at station 34XXXX in office B. On removing the receiver, the lineswitch RS' operates and selects an idle first selector such as FS'. When the first office-designating digit 3 is dialled, the first selector FS' is raised to the third level and rotates in to select an idle trunk in the group 3, extending to the office B, where these trunks terminate in thousands selectorssimilar to MS2. When the next digit, 4, of the office designation is dialled, the digit is cancelled by the thousands selector in use. When the next digit of the number is dialled the thousands selector is operated to select an idle hundreds selector, and the latter then responds to the fourth digit of the number to select an idle connector in the desired group. The last two digits then operate the connector to complete the connection.

Suppose now the subscriber at station 23XXXX desires to obtain connection with a station, such as 65XXXX in office E. On removing the receiver to initiate the call the line-switch RS' operates as before to select an idle first selector, for example, the selector FS'. On dialling the first office digit 6, the selector FS' is raised to the sixth level, and then selects a trunk leading to an idle office selector such as OS', in office E. The office selector OS' responds to the second office digit 5 and is raised to the fifth level, thereupon selecting an idle local thousands selector such as

105

110

115

120

125

130

135

140

145

150

MS4. The four local digits now control the operation of the thousands selector MS4, a hundreds selector, and a connector to complete the desired connection.

- 5 It may be assumed now that a subscriber at station 65XXXX desires to obtain a connection with another subscriber in the same office, that is, in the tandem office, whose number will be 65XXXX. Upon removing the receiver, the 86
10 lineswitch RS2 is operated in the usual manner to select a trunk line leading to an idle first selector, such as FS2. The first digit (6) of the office designation is now dialled, and this digit is cancelled by the first selector FS2, the selector at 85
15 the same time altering its circuit so that the next digit will not be cancelled. The operation of establishing a local connection in the tandem office, therefore, differs from the operation of establishing a local connection in an outlying office, such as the office A. In the tandem office, 90
20 the first digit of the office designation is cancelled, whereas in the outlying office the first digit of the office designation is effective and the second digit is cancelled. Continuing with the operation, 95
25 when the second digit (5) of the office designation is dialled, the selector FS2 is raised to the fifth level, and thereupon selects a trunk line leading to an idle thousands selector, such as MS4, it being understood that the banks of the 100
30 selector, such as FS2, are multiplied with the banks of the office selectors. The four local digits of the number are now dialled and are effective to operate the thousands selector MS4, a hundreds selector, and a connector to select and complete 105
35 the connection to the desired subscriber's line.

Suppose now that a subscriber at station 65XXXX desires to obtain connection with a subscriber in office A, for instance the subscriber at 110
40 station 23XXXX. When the receiver is removed the lineswitch RS2 operates as usual to select an idle first selector, such as FS2. The first office digit 2 being dialled, this digit is cancelled by the selector FS2. When the second office digit 3 is 115
45 dialled, the selector FS2 is raised to the third level, and selects an idle trunk line in group 23, leading to a thousands selector, such as MS3, in office A. The next four digits of the number, the local digits, operate the thousands selector MS3, a hundreds selector, and a connector to complete 120
50 the desired connection.

It will be seen from the foregoing that the establishment of a call from a station, such as 23XXXX in an outlying office to a station, such as 65XXXX, in the tandem office, differs from the establishment of a connection in the reverse direction. In setting up a call from a station in office A to a station in office E, all the digits are effective, while in setting up a call from a station 125
60 in office E to a station in office A the first office digit is cancelled.

Considering now the establishment of a tandem connection through office E, it may be assumed that the subscriber at station 23XXXX in office A desires to obtain connection with a subscriber whose number is 76XXXX in office F. On removing the receiver, lineswitch RS1 operates in the usual manner to select an idle first selector, such as FS1. When the first office digit 130
65 7 is dialled, the selector FS1 is raised to the seventh level, and thereupon selects an idle trunk line in the group 6-5-4-7, leading to an office selector such as OS1 in the tandem office E. The second office digit 6 may now be dialled, resulting in operating the office selector OS1 to the 135
70

sixth level. The office selector OS1 then automatically rotates and selects an idle trunk in group 76, leading to the office F, where the trunk terminates in a thousands selector similar to MS3. The four local digits of the number are 86
75 now dialled and serve to operate the thousands selector MS3, a hundreds selector, and a connector, to complete the desired connection.

The calls which have been described in the foregoing are typical, and the foregoing explanation, therefore, will make it clear how the various types of calls involving the other offices are established. Local connections in offices B, C, D, and F, for instance, are established in the same manner as are calls in office A. Calls from an office, such as B, to an office, such as C, involving the use of direct trunks between outlying offices, are established in the same way as calls between office A and office B. Tandem calls from offices, such as D and F, to offices, such as A or B, are established in the same way as the hereinbefore-described tandem call from office A to office F. It will not be necessary, therefore, to describe the calls in detail. 130

It will be seen that an economical trunking layout has been devised applicable especially to moderate sized multi-office networks, and possessing a number of advantages. Although both tandem and direct trunking are used, all calls are set up in accordance with a uniform numbering system. 135
140 The drop-back selectors used are of the simplest type, as they always cancel the first digit only and are not required to discriminate as to the value of the digit. The number of switches involved in any call is reduced to a minimum. Only on tandem calls are the full complement of five switches required and on all other calls only four switches are used.

Referring now to Fig. 3 this drawing shows an automatic telephone system comprising two offices. Each office comprises two groups or "thousands" of subscribers' lines. The office to the left of the dotted line will be referred to as the No. 1 office, while the office to the right of the dotted line will be referred to as the No. 2 office. A uniform five-digit numbering system is used, that is, each subscriber's telephone number comprises five digits. The first digit in each number is the office designating digit. A particular feature of the invention is the use of one of the local groups 145
150 or "thousands" in each office as a tandem switching point on calls incoming from the other office.

Referring to office No. 1, as mentioned hereinbefore, this office comprises two main groups of subscribers' lines. The first group may be referred to as the third "thousand" and comprises 155
160 600 subscribers' lines. Each subscriber's line, such as the line of station 13520, has individual thereto a rotary lineswitch such as RS3, which has access to a group of combination first, second, and third selectors, such as CS1. There may be a number of groups of these combination selectors, depending on the capacity of the rotary lineswitches. The other main group of subscribers' lines may be designated as the fourth 165
170 "thousand" and also comprises 600 subscribers' lines. A station in this group is shown, designated as station 14520. The line extending from this station terminates in a rotary lineswitch, RS5, which has access to a group of combination first, second, and third selectors, such as CS2. 175
180

The combination first, second, and third selectors, such as CS1 and CS2, are of the drop-back type and are of the general type of switch which is shown in the Lomax patent herein- 185
190

before referred to. The combination selectors, such as CS1 and CS2, however, are arranged to drop back on two levels instead of one. The drop-back selector shown in Fig. 2 of Lomax, therefore, is modified to the extent of having a second set of shaft springs like the set there shown. The springs 9 of the second set are connected in multiple to springs 9 of the first set, while springs 10 of the second set are connected in series with springs 10 of the first set.

The six upper levels of the combination selectors, such as CS1, are connected in multiple and give access to six groups of connectors, such as connector C1, which is reached by way of the fifth level. The connector C1 and the other connectors of this group have access to subscribers' lines in the fifth "hundred" of the third "thousand".

The upper six levels of the combination selectors CS2 are also connected in multiple and give access to six groups of connectors, including the connector C2, reached by way of the fifth level. The connectors of the group including connector C2 have access to the fifth "hundred" in the fourth "thousand". The third level of the selector CS2 is also multiplied, as indicated in the drawings. For convenience, the bracket which indicates the multiple connections includes the fourth level, but it is immaterial whether this level be multiplied or not, unless the fourth level is to be used for trunking to connectors, as will be explained subsequently.

The fourth level of the combination selectors, such as CS1 of the third "thousand", gives access to trunk lines which terminate in hundreds selectors, such as HS2, in the fourth "thousand". The banks of these hundred selectors are multiplied with the banks of the combination selectors such as CS2.

The third level of the combination selectors CS2 of the fourth "thousand" gives access to trunk lines leading to hundreds selectors, such as HS1, in the third "thousand". The banks of the hundreds selector HS1 are connected in multiple with the banks of the combination selectors, such as CS1.

The No. 2 office comprises two main groups, the same as the No. 1 office, and in general is laid out like the No. 1 office. It will not be necessary, therefore, to go over the trunking in detail.

The interoffice trunking may now be referred to. The second level of the combination selectors, such as CS1, in the No. 1 office, give access to a group of trunk lines which lead to the No. 2 office, and they terminate in a group of tandem selectors, such as TS3. These tandem selectors have their banks connected in multiple with the banks of the combination selectors CS3 and the banks of the hundreds selectors HS3. The second level of the combination selectors CS2 in the No. 1 office give access to a group of trunk lines leading to the No. 2 office, and there terminate in a group of tandem selectors, such as TS2. Tandem selectors TS2 have their banks connected in multiple with the combination selectors CS4 and the hundreds selector HS4. The foregoing arrangement is indicated in the drawing. It may be preferred, however, and ordinarily the practice

would be, to have a certain number of first-choice trunks accessible from the combination selector CS1 and leading to tandem selectors such as TS3, a corresponding number of first-choice trunks accessible to the combination selectors CS2 and leading to the tandem selectors TS2, and a group

of over-flow trunks accessible in common to the combination selectors CS1 and CS2 and leading to tandem selectors which are distributed between the third and fourth "thousands" of the No. 2 office.

The trunking from the No. 2 office to the No. 1 office may be the same as has been described for trunking from the No. 1 office to the No. 2 office. However, a somewhat simpler arrangement may be adopted in case it is unnecessary to take advantage of all the features of the present invention. As shown in the drawings, the first level of the combination selectors CS3 in the No. 2 office is multiplied with the first level of the combination selectors CS4, and from these multiply connected levels a single group of trunk lines extends to the tandem selectors, such as TS1 in the No. 1 office. The banks of the tandem selectors, such as TS1, are connected in multiple with the banks of the combination selectors CS2 and the hundreds selector HS2, at least the multiple extends over all those levels which are used for trunking to connector switches and to the hundreds selector HS1.

The levels at which the various drop-back selectors cancel digits is determined by the numbering. In the present layout, the combination selectors, such as CS1, cancel the digits 1 and 3, and are, therefore, arranged to drop back on these levels. The combination selectors such as CS2 cancel digits 1 and 4 and are arranged to drop back on the corresponding levels. Combination selectors CS3 and CS4 are the same as combination selectors CS1 and CS2, respectively, except that they cancel the digit 2 instead of the digit 1. Tandem selectors TS1 are arranged to cancel the fourth digit, and these selectors, therefore, drop back on this level. The tandem selectors TS2 are similar to the tandem selectors TS1. The tandem selectors TS3 are the same, except that they are arranged to cancel the third digit instead of the fourth. Appropriate labels on the drawings indicate the levels on which the various selectors drop back.

It may be mentioned that the tandem selectors described herein may be of the type disclosed in the Lomax patent hereinbefore referred to.

It may now be assumed that the subscriber at station 13520 desires to extend a call to station 13510, in other words, to a station in the same main group in the same office. Upon removing the receiver, the lineswitch RS3 operates and extends the line to an idle combination selector such as CS1. On dialling the digit 1, the selector CS1 operates to cancel the digit. It will be understood that the selector is raised to the first level and then releases. The next digit is the digit 3, and this digit is cancelled also. Thus the combination selector CS1 is in normal position after the dialling of the first two digits. The next digit dialled is the digit 5, which raises the combination selector CS1 to the fifth level, whereupon the selector rotates in and selects a trunk line leading to an idle connector, such as C1. The next two digits, 1 and 0, operate the connector C1 to complete the desired connection. The switches release in the usual manner when the receiver is hung up at station 13520.

It may be assumed now that the subscriber at station 13520 desires to obtain a connection with the subscriber at station 14520, that is, to a subscriber in the other main group in the same office. Upon lifting the receiver, the rotary lineswitch RS3 operates to find an idle combination selector

80

110

115

120

125

130

135

140

145

150

such as CS1. The first digit dialled is the digit 1, which is cancelled as before described. The second digit dialled is the digit 4, which raises the combination selector CS1 to the fourth level.

- 5 Hunting in this level in the usual manner, the combination selector CS1 selects an idle trunk line leading to a hundreds selector, such as HS2. The next digit dialled is the digit 5, which operates the hundreds selector HS2 to the fifth level, 80 on which level the selector rotates in order to find an idle connector, such as connector C2. The digits 2 and 0 operate the connector C2 to complete the connection to the desired station, 85 14520.

- 15 A call from station 14520 to station 13520 follows the same principle as the call just above described. Selector CS2 cancels the first digit 1, the second digit 3 is used to raise the selector CS2 to the third level and select a hundreds 90 selector such as HS1, the third digit 5 operates the hundreds selector HS1 to select an idle connector, while the last two digits operate the connector, such as C1, to complete the desired connection. Calls from station 14520 to another 95 station within the same main group, that is, within the four "thousand" group, are established in the same way as was described in the case of station 13520 calling station 13510.

- It will now be assumed that the subscriber 100 at station 13520 desires to obtain a connection 105 with the subscriber at station 24550, that is, to a subscriber in the fourth "thousand" of the No. 2 office. On removing the receiver, the rotary lineswitch RS3 operates in the usual manner to select an idle combination selector such as CS1. 110 On dialling the first digit 2, the office designating digit, the combination selector CS1 is raised to the second level, whereupon it selects an idle trunk line leading to the No. 2 office, and there 115 terminating in a tandem selector, such as TS3. The next digit dialled is the digit 4, which operates the tandem selector TS2 to the fourth level. On this level the tandem selector hunts for an idle trunk leading to a hundreds selector, 120 such as HS4. The next digit dialled is the digit 5, which operates the hundreds selector HS4 to the fifth level, whereupon the hundreds selector selects a trunk line leading to an idle connector, such as C4. The last two digits, 5 and 0, operate 125 the connector C4 to complete the desired connection to station 24550.

- It may be assumed now that the subscriber at 130 station 13520 desires to extend a connection to station 23530 in the third "thousand" group of the No. 2 office. On removing the receiver, the lineswitch RS3 operates as usual, selecting an idle combination selector, such as CS1. Responsive to the first digit 2, the combination selector CS1 135 selects a trunk leading to the No. 2 office and there terminating in a tandem selector, such as HS3. The next digit dialled is the digit 3, which is cancelled by the tandem selector TS3. The next digit dialled is the digit 5, which operates the tandem selector TS3 to the fifth level, on 140 which level it selects an idle trunk leading to a connector, such as C3. Connector C3 responds to the last two digits, 3 and 0, and completes the desired connection to station 23530.

- 70 The foregoing calls are typical, and the explanation given will enable any one to readily see how all of the other possible calls are set up.

- As regards calls made within the No. 1 office, it will be observed that some of these calls are 145 completed by means of only two switches, while

other calls require three switches for their completion. Thus, a call from station 13520 to station 13510 requires only a selector, such as CS1, and a connector, such as C1. The same is true of a call from station 14520 to another station 80 in the four "thousand" group. Intergroup calls, however, require three switches for their completion. For instance, a call from station 13520 to station 14520 requires a combination selector, such as CS1, a hundreds selector such as HS2, 85 and a connector C2 for its completion. It will be obvious that under ordinary circumstances about half the calls local to the No. 1 office can be completed in this system by means of only two switches. 90

The foregoing leads up to certain provisions which can be availed of in order to insure that the possible economies are secured, or to increase the normal economies which are inherent in the system. It will be clear that the saving 95 of one switch on fifty percent. of the local calls will only obtain if fifty percent. of such calls initiated in the No. 1 office, for instance, are for stations which are in the same group as the calling stations. If one is to be satisfied with 100 this saving, the best plan to follow is to give the lineswitches, such as RS3 and RS5, equal access to the selectors CS1 and CS2 in both "thousands". This will insure that approximately half the calls from any calling line go to combination selectors, such as CS1, in the third "thousand", while the other half go to combination selectors, such as CS2, in the fourth "thousand", and will insure that approximately half the time the calling and called stations will be in the same main group. 110

It is possible, however, to obtain a considerably greater economy by putting in effect a routine of checking the calls after the exchange is installed so as to determine, in the case of busy calling lines, which stations are the most frequently called. In the case of station 13510, for instance, service observations may indicate that a very large percentage of the calls from this station go to a called station in the fourth "thousand" group. This being the case, an economy 120 of switches can be effected if the lineswitch assigned to station 13510 has access to combination selectors, such as CS2 in the fourth "thousand" group rather than to combination selectors, such as CS1, in the third "thousand" group. The shifting 125 of the traffic from one group of combination selectors to the other is very readily taken care of by means of an intermediate distributing frame. The drawings indicate in the upper left-hand corner a main distributing frame labeled M. D. F., 130 and an intermediate distributing frame labeled I. D. F. According to known practice, the outside lines terminate on one side of the main distributing frame, and from the other side of the main distributing frame cables extend to one side of 135 the intermediate distributing frame. At this point, also, are terminated cables coming from the connector bank multiples. On the other side of the intermediate distributing frame cables run to the lineswitches. It will readily be seen now 140 that any line, such as the line of station 13510, can be cross-connected to a lineswitch which has access to combination selectors such as CS3 in the third "thousand" or to a lineswitch, such as RS4, which has access to combination selectors, such as CS2, in the fourth "thousand". It may be assumed that station 13510, from the telephone number, was originally cross-connected to a lineswitch having access to combination selector CS1, but the drawing indicates that the cross-connec-

tion has been changed to lineswitch RS4 which has access to combination selectors in the fourth "thousand".

It will readily be seen that considerable may be accomplished along the plan outlined, with a view to getting calling and called subscribers in the same main group as far as possible, with the idea of using only two switches for the maximum number of calls. Where an automatic exchange, following this plan, is to be installed in place of a manual exchange, possibly sufficient data on the parties customarily called by each subscriber can be obtained beforehand so as to effect a considerable saving at the start. In other cases, traffic observation which takes into account not only the calling party but the party called will indicate how the cross-connections to lineswitches may be changed to advantage for the purpose of obviating the necessity of installing additional exchange equipment as the traffic grows.

As regards the tandem trunking between offices, it will be observed that the feature involved is to use one of the "thousands" as a tandem switching point, which enables one switch to be saved on approximately fifty percent. of the tandem calls.

With the arrangement of trunking, as shown in the drawings, for calling from the No. 1 exchange to the No. 2 exchange, considerably more than fifty percent. of the calls may be included in the group which requires less switches than ordinarily. It will be observed that the combination selectors CS1 have access to tandem selectors in the third main group of the No. 2 office, while the combination selectors CS2 have access to trunks extending to the tandem selectors in the fourth main group of the No. 2 office. At least the first-choice trunks accessible to the combination selectors CS1 and CS2 are assumed to be connected in this manner. It follows that if a subscriber in the No. 1 office, such as the subscriber at station 13520, confines his interoffice calls, to a large extent, to one or two particular subscribers in the No. 2 office, these subscribers should, if possible, be terminated in the third "thousand" group of the No. 2 office, or if this is impossible the line leading from station 13520 should be changed over to a lineswitch which has access to the combination selector CS2. The first condition can usually be met where the particulars of the calling are known beforehand, and care can be taken to assign the telephone numbers so as to bring about the desired results. In the case where this is not done, however, or where the calling habits change, the desired condition can best be brought about by changing to different lineswitches, as mentioned, for it is generally considered undesirable to change a subscriber's telephone number. Of course, care must be taken that a change in the intermediate frame jumping to provide economies on interoffice calls does not interfere with economies on calls within the same exchange, but, if a record is kept of both local and interoffice calls made by particular lines, the best cross-connecting to give the maximum economies in both cases can readily be worked out.

Something can be done even with the trunking shown for handling calls from the No. 2 office to the No. 1 office in order to affect a saving of switches. A survey will generally show that a number of stations in the No. 2 office habitually direct a large proportion of their calls to particular stations in the other office. This survey will then give a small group of stations, which, as

called lines should be assigned to the main group in which the incoming tandem selectors are located, and thus avoid the necessity of using a separate hundreds selector on calls to these stations.

For the sake of simplicity, the system has been described as comprising two offices, each office comprising two main groups of 600 lines each. It will be appreciated that if only 600 lines are used in each main group, at least two levels of the combination selectors, such as CS1, are wasted. The second level is used for interoffice trunking, while the fourth level is used for inter-group trunking, but no use is made of the first and third levels. It will readily be appreciated now that, by following the principles set forth in the patent to Martin or the patent to Bellamy hereinbefore referred to, the combination selectors can each be provided with a relay which will open the release magnet circuit after the second digit has been cancelled. This will prevent the combination selectors from cancelling the digits 1 and 3 if they are dialled the second time, and will enable these two levels to be used for trunking to connector switches. Thus, the size of each of the main groups can be increased to 800 lines if desired.

What is claimed is:

1. In a telephone system, a tandem office, a plurality of non-tandem offices, subscribers' lines connected to said offices all having the same number of digits in their telephone numbers, means including a certain number of automatic switches for completing a tandem call, means including a lesser number of switches for completing a non-tandem call, and means in a certain switch which is used exclusively for non-tandem calls for cancelling a digit.

2. In a telephone system, a tandem office, a plurality of non-tandem offices, subscribers' lines connected to said offices all having the same number of digits in their telephone numbers, means including a certain number of switches for completing a tandem call, means including a lesser number of switches for completing non-tandem calls, and means for cancelling the first or second digit on any non-tandem call depending on whether the call originates in the tandem office or in a non-tandem office.

3. In a telephone system, two offices, non-drop-back first selectors in the first office, drop-back first selectors in the second office, drop-back local selectors in the first office accessible to the first selectors therein, and non-drop-back local selectors in the first office of the same order as the first mentioned local selectors accessible over trunk lines to the said first selectors in the second office.

4. In a telephone system, an office, a series of switches in said office for setting up local connections, a first switch in said series responsive to the first digit of a subscriber's number to select the second switch of the series, means in the second switch for cancelling the second digit of the number, said second switch responsive to the third digit of the number, and other switches in said series responsive to the remaining digits.

5. In a telephone system, a plurality of offices, a tandem office, drop-back first selectors in said tandem office, non-drop-back first selectors in said offices, trunks accessible to said non-drop-back selectors extending to said tandem office, non-drop-back office selectors terminating said trunks, and multiple connections between the 150

- banks of said drop-back selectors and said office
selectors.
6. In a telephone system, a tandem office, a
non-tandem office, a second non-tandem office,
5 trunks extending from said first non-tandem
office to said second non-tandem office, drop-back
selectors terminating said trunks, trunks extending
from said tandem office to said second non-
tandem office, non-drop-back selectors terminat-
10 ing said last mentioned trunks, and multiple con-
nections between the banks of said drop-back se-
lectors and said non-drop back selectors. 80
7. In a telephone system, an office comprising
two groups of lines, selectors having access only
15 to the lines of one group, other selectors having
access to the lines of the other group, incoming
selectors having their banks connected in multi-
ple with the banks of the first-mentioned selec-
tors, and trunk lines leading from said banks to
20 selectors whose banks are connected in multiple
with the banks of the second mentioned selectors. 85
8. In a telephone system, an office comprising
two groups of lines, two groups of selectors han-
dling calls to the two groups of lines, respec-
25 tively, and other selectors handling calls to one group
of lines and also functioning as tandem selectors
to handle calls to the other group of lines. 90
9. In a telephone system, an office comprising
two groups of lines, an order of selectors allotted
30 to one group, selectors of the same order allotted
to the other group, a second office, trunks incom-
ing from said second office, selectors terminating
said trunks and having their banks multiplied
35 with the banks of said first mentioned selectors,
trunks leading from said banks, and selectors ter-
minating said last mentioned trunks and having
their banks multiplied with the banks of said sec-
ond mentioned selectors. 100
10. In a telephone system, an office comprising
40 two groups of lines, means for establishing con-
nections between the lines of different groups by
a certain number of switches, means for estab-
lishing connections between lines of the same
45 group by means of a smaller number of switches,
and means for readily changing any line from
one group to another so that such line will be in
the same group as a line which is frequently
called. 110
- 50
- 55
- 60
- 65
- 70
- 75
11. In a telephone system, two groups of auto-
matic equipment each comprising selectors and
connectors, lines having called branches accessi-
ble to the connectors, calling branches for said
lines having access to said selectors, and means
for changing any calling branch so that particu-
lar calling lines have their calling branches in ac-
cess to selectors in the same group as the con-
nectors which are used for connecting to the lines
most frequently called. 120
12. In a telephone system, two offices, two groups
of tandem selectors in one office, sub-
scribers' lines accessible to said tandem selectors
by way of a varying number of additional
switches, and means for insuring that a calling
line in the other office will use a tandem selector
which has access to the desired line by way of
the minimum number of switches. 125
13. In a telephone system, two offices, a calling
line in the first office, a called line in the second
office which is frequently called from said first
line, two routes by which calls from the first office
may be extended to the said called line, one route
including less switches than the other, and means
for routing calls from said calling line to said 130
called line over the route which includes the
smaller number of switches. 135
14. In a telephone system in which connections
from either of two stations are extended to a
third station by automatic switches operated re-
sponsive to identical series of digits, means for
cancelling one particular digit only of the series
in calls from one of said stations, and means for
cancelling a different digit of the series in calls
from the other of said stations. 140
15. In a telephone system in which connections
from either of two stations are extended to a
third station by automatic switches set responsive
to a number including a two-digit office designa-
tion, means for cancelling only the first digit of 145
the office designation in calls from one of said
stations, and means for cancelling only the sec-
ond digit of the office designation in calls from the
other of said stations. 150
